UNITED STATES PATENT OFFICE

2,444,969

WELT HOLD-DOWN

Charles K. Woodman, Beverly, Mass., assignor to
 United Shoe Machinery Corporation, Flemington, N. J., a corporation of New Jersey

Application July 15, 1946, Serial No. 683,653

10 Claims. (Cl. 12—33)

1

This invention relates to welt holdowns and particularly to the provision of an improved welt holdown mechanism for use in machines by which soles are attached to shoes with cement and pressure.

Recently developed types of cement which have come into extensive use for sole attaching require considerably more pressure than is required to produce a satisfactory bond with the pyroxylin cement which was formerly used almost exclusively. Consequently, the welt holdowns which are employed in cement sole attaching machines must be capable of sustaining, without collapsing, a higher degree of pressure than was formerly employed but must still be sufficiently flexible to enable them to be conformed easily to the contour of the shoe being operated upon, and the pressure devices which are used to cause the holdowns to press the welt of a shoe against the margin of the outsole must be capable of producing an increased amount of pressure with a given amount of effort on the part of the operator.

It is an object of the present invention to provide an improved welt holdown which will support and apply adequate pressure to the welt of a shoe to cause it to adhere securely to the sole, without materially interfering with the manipulation of the work or its insertion in, or removal from, the sole attaching machine.

In contrast to the soft rubber welt pressing members commonly employed in welt holdowns a feature of the present invention resides in a welt holdown comprising a U-shaped series of nested concavo-convex cylindrically curved plates combined with means for holding said plates in contact with each other. Preferably, the plates will be held in contact by a flexible cable passing through them and provided with means, such as as springs, for engaging the endmost plates of the series and holding all the plates in contact with each other. Although the plates may be of hard rigid material such, for example, as metal, capable of sustaining heavy pressure without collapsing, the welt engaging member as a whole is sufficiently flexible to conform readily to the forepart of a shoe and need not be bulky enough to interfere with the necessary manipulation and positioning of the shoe.

In the illustrated embodiment of the invention the side portions of the welt pressing member are so supported that they are continuously subjected to a torsional force tending to lift said member and simultaneously tilt its side portions outward, causing it normally to assume a posi-

tion in which a shoe to be operated upon is most easily inserted.

Other features of the invention, including improved means for pressing the welt engaging member into the welt crease of a shoe and improved mechanism for pressing the welt pressing member against the welt, will become apparent from reading the following detailed description of one successful embodiment of the invention in connection with the accompanying drawings, in which

Fig. 1 is a view in front elevation of the apparatus;

Fig. 2 is a plan view showing the welt pressing member and its mountings;

Fig. 3 is an angular view on an enlarged scale of the welt pressing member;

Fig. 4 is an enlarged sectional view of a detail of the welt pressing member;

Figs. 5 and 6 show details of apparatus for pressing the welt engaging member into the welt crease of a shoe;

Fig. 7 is a view in side elevation of manually operable mechanism for pressing the welt pressing member against the welt; and

Fig. 8 is a plan view of one of the concavo-convex plates of the welt pressing member.

Referring now to the drawings, 10 indicates the pad box and 12 the press pad of a sole attaching machine by which an outsole may be cement attached to a shoe 16 having a welt 18. A well-known machine of this type which is in extensive use is dissolved in United States Letters Patent No. 2,047,185, granted July 14, 1936, upon application of Milton H. Ballard, et al., to which patent reference may be had for a full description of the mechanism of the machine which constitutes no part of the present invention.

40 Pivoted at 20, 22 (Fig. 2) upon the pad box 10 are plates 24, 26 which are slotted concentrically with their respective pivots as shown at 28, the slotted portions overlapping and cooperating with a locking bolt 30 which may be operated to prevent the plates from swinging about their pivots or released to permit such swinging movement. This locking bolt, as illustrated, may be the same as the locking bolt 720 shown in the aforesaid patent.

45 Springs 32, 34 anchored at 33 and 35, respectively, to the pad box 10 are attached to the plates 24, 26 at such points as always to tend to rotate the plate 24 in a clockwise direction and the plate 26 in a counterclockwise direction, as viewed in Fig. 2.

Inasmuch as the movable parts at the two sides of the pad box are alike, it will be sufficient to describe the parts at one side in detail. Pivoted at 36 to an overhanging portion 37 of an upright 38 integral with the plate 26 is a gage arm 40 which is freely movable vertically about the pivot. A rearward extension 42 is adjustably mounted upon the under side of the arm 40 by means of a screw and slot connection 44 and has pivoted upon its rear end portion, at 46, a sole gage 48 which is best shown in Figs. 2 and 5. A pin 47 extending downward from the gage member 48 into an arcuate slot in the extension 42 limits the scope of the turning movement of the gage about the pivot 46. By reason of the pivotal mounting at 36 of the gage arm 40 by which the sole gage is carried, the gage is free to rest loosely upon the pad 12, rising or falling as may be required to follow the contour of the upper face of the pad as the gage arm is swung inwardly or outwardly thereof.

Carried by the sole gage 48, above the sole engaging portion thereof, is a presser plate 50 having a shank 52 slidable in a horizontal guideway 54. The shank 52 is bored out to receive a compression spring 56, one end of which bears against the end of the bore and the other end of which bears against a flattened face of a pin 58 secured in the bottom of the guideway 54.

The shank 52 is slotted as shown at 60 to receive the pin 58 and the outer end of said shank is adapted to abut against an adjustable stop screw 62 which is threaded through the outer end portion of the gage member 48. A spring clip 64 which embraces the screw 62 exerts enough friction upon the screw to prevent the latter from turning accidentally.

A U-shaped flexible welt pressing member 66 (see Figs. 2 and 3) comprises a series of nested, concavo-convex, cylindrically curved plates 68 arranged with their curved faces in movable sliding contact with each other and with their axes of curvature extending vertically. The shape of each plate 68, as seen in elevation, is approximately as shown in Fig. 5 and, as seen in plan, substantially as shown enlarged in Fig. 8. The lower ends of the plates 68 and, consequently, the lower edge of the welt pressing member 66, of which they are constructed, are formed to enter the welt crease of a shoe and bear upon the upper face of the welt to press the latter into firm contact with the outsole to which it is to be cement attached.

The plates 68 are strung upon flexible cables 70, 72, the ends of which extend beyond the assembly of plates 68 as shown in Figs. 2, 3 and 4 and are surrounded by compression springs 74, held under tension by the flanged heads 76 of tubes 78 firmly affixed to the ends of the cables as by soldering or brazing. The cables 70, 72 pass through holes 80, 82 in the plates 68 which holes are enough larger than the cables to provide for a small amount of sliding movement of the plates upon each other. The vertical sliding movement of the plates relative to each other is sufficient to allow the welt pressing member as a whole to conform to the vertical contour of the shoe and the relative sliding movement in a horizontal sense, which is also permitted by the holes being larger than the cables, facilitates the fitting of the welt pressing member closely around the forepart of the shoe.

In addition to the two cables 70, 72, an unattached, close-wound wire spring 84 extends loosely throughout most of the series of plates 68, ter-

minating somewhat short of the two ends of the assembly. This spring is sufficiently stiff and resilient so that its normal tendency to straighten out causes the U-shaped welt pressing member 66 to open out to a size and shape which will permit easy insertion of a shoe when no inward pressure is exerted upon the side portions of said member.

Attached to the sides of the U-shaped member 66 are lugs 86 provided with vertical holes 88 for the reception of pivot pins 90 by which the welt pressing member is connected to blocks 92 mounted to turn and slide freely upon supporting rods 94 extending alongside the side portions of the member 66. The forward ends of the rods 94 are pivoted at 96 for vertical swinging movement in swivel blocks 98, each of which has a depending stem 100 which is rotatable in a bearing in the overhanging portion 37 of one of the uprights 38. Each stem 100 has a circumferential groove 104 engaged by a detent 106 held in place by a nut 108. The effect of this mounting is that the supporting rod 94 is movable vertically about the horizontal pivot 96 and horizontally about the axis of the vertical stem 100. A torsion spring 110 surrounding the pivot 96 tends continually to elevate the supporting rod 94.

Each of the supporting rods 94 is surrounded by an open wound, combination torsion and compression spring 112, one end of which is anchored in one of the blocks 92 and the other end of which is anchored in the enlarged forward end 114 of the rod near the pivot 96. The springs 112 at the two sides of the apparatus are wound in opposite directions, each being so wound that it tends continually to rotate the block 92, in which it is anchored, around the axis of the rod 94 in a direction to lift the adjacent side of the welt pressing member 66 and tilt its upper edge outward, thus presenting the welt pressing member in the most advantageous position for easy insertion of a shoe.

The pressure device for pressing the member 66 downward upon the welt of the shoe is broadly similar to that disclosed in United States Letters Patent No. 2,138,960, granted December 6, 1938, upon application of Sidney J. Finn, but embodies substantial improvements which make it effective to produce an increased amount of pressure with a given amount of effort on the part of the operator.

Referring particularly to Figs. 1 and 7, a U-shaped pressure block 116 is pivotally suspended on studs 118 secured in a block 120 which is mounted to slide vertically upon a post 122 which carries the toe pad 124 by which the forepart of a shoe is pressed downward upon the press pad 12. The weight of the pressure device is supported by compression springs 126 which tend to hold the block 120 elevated.

Pins 128, extending from opposite sides of the block 120 are engaged in slots 130 in a bifurcated lever 132, one end of which is pivoted at 134 upon a bracket 136 depending from the pressure head 138 of the sole attaching machine. The other end of the lever 132 is provided with a block 140 adapted to be engaged by an adjustable pressure transmitter 142 which is rotatably mounted on a pin 144 secured in a lever 146 movable about a stud 148 secured in the pressure head 138. The pressure transmitter 142 is formed with an arm 150 in which is a rotatable plug 152 through which passes the shank portion of a screw 154 which is freely rotatable but is restrained from longitudinal movement through the plug 152 by a

collar 156 and the hub of a head 158, both of which are fixed upon the screw. The threaded portion of the screw is engaged in a threaded hole in a plug 160 which is similar to the plug 152 and is held in the outer end of the lever 146. The curved lower face 162 of the pressure transmitter is eccentrically related to the pin 144, with the result that when the screw 154 is turned, and the transmitter is rocked about the axis of the pin 144, the space between the face 162 of the transmitter and the top of the block 140 is varied as may be required to adjust the apparatus according to the height of the surface of the press pad 12 and the thickness of the welt and sole of the shoe to be operated upon. With any given adjustment, however, the transmitter 162 and the lever 146 are in fixed relation to each other.

Pressure is applied manually, through the pressure device, to the welt pressing member 66 by pulling forward upon a hand lever 164 which is rotatable about a stud 166 carried by a bracket 168 integral with the pressure head 138. A cam face, comprising an eccentric portion 170 and a semi-circular recess 172 formed upon the lever 164, is arranged to be engaged by a cooperating nose 174 of the pressure transmitter 142. The lower edge of the hand lever member 164 is curved concentrically with the stud 166 and is serrated as shown at 176. The serrations are engageable by a pawl 178 under the influence of a spring 180 which is anchored to a pin 182 inserted in the lever 146, and a torsion spring 184 which bears against a pin 186 fixed in the lever 164 tends, when the pawl 178 is disengaged, to throw the lever back to the position shown in Fig. 7, in which the parts are shown in the positions assumed at the end of a cycle of operation, the pawl having been disengaged from the serrations 176 by a tail portion 188 of the pawl striking an adjustable, but normally stationary, stop screw 190 at the end of the upward movement of the pressure head 138 of the machine. At the beginning of the next cycle, after a sole and shoe have been positioned upon the pad 12, the pressure head 138 is lowered to press the shoe and sole firmly down upon the pad 12 by means of the toe pad. During this movement the tail of the pawl leaves the stop screw 190, permitting the pawl to engage the serrations 176 and remain in engagement therewith until the end of the upward return movement of the pressure head 138 after the sole has been attached to the shoe.

When the shoe and sole have been pressed down upon the pressure pad 12 by the toe pad 124, the operator pulls the hand lever 164 forward imparting an initial rapid downward movement to the pressure transmitter 142 until the projection on the cam face at the juncture of the recess 172 and the eccentric portion 170 thereof has passed over the nose 174 of the transmitter and the eccentric portion 170 of the cam face is riding upon said nose, whereupon the transmitter continues to be depressed more slowly at a rate determined by the eccentricity of the portion 170 of the cam face, affording an increased mechanical advantage and enabling the operator to exert a greatly increased amount of pressure upon the work with a given amount of effort.

In the downward movement of the transmitter 142 it engages the block 140, depressing the bifurcated lever 132, and, through the pin and slot connection 128, 130, lowers the block 120 and the pressure block 116 against the tension of the supporting springs 126, the parts being

so related and proportioned that when the hand lever 164 is pulled far forward the pressure block 116 pressed down heavily upon the welt supporting member 66, causing said member to press the welt 18 down into firm contact with the sole 14.

In the operation of the machine the operator positions the sole upon the press pad 12 between the sole gages 48 which rest upon the surface of the pad and yield outwardly independently, to permit the sole to be placed as desired. The sole gages are now locked by the locking bolt 30 to preserve the position of the sole. The welted shoe is next inserted in the welt pressing member 66 which is yieldingly held rearward, with the upper portions of its sides tilted outward, by the combination torsion and compression springs 112, in a position most favorable for easy insertion of the shoe. The shoe is so placed in the welt pressing member that the inturned lower edge of the member occupies the crease between the welt and the upper of the shoe as illustrated in Fig. 5.

The shoe and the welt pressing member 66 are now pushed forward and downward to position the shoe properly upon the sole 14, the spring pressed presser plates 50 yielding sufficiently, if necessary, to permit the welt pressing member to be moved forward between them and serving to straighten up the sides of the welt pressing member and to press its lower edge inward snugly into the welt crease of the shoe. When the shoe has been accurately registered upon the sole, the machine is started and the operation of attaching the sole to the shoe by pressure proceeds as above described.

Having described my invention, what I claim as new and desire to secure by Letters Patent of the United States is:

1. A welt holdown comprising a U-shaped series of nested, concavo-convex, cylindrically curved plates arranged with their curved faces in movable sliding contact, and means for holding said plates in contact with each other.

2. A welt holdown comprising a U-shaped series of nested, concavo-convex, cylindrically curved plates, a flexible cable passing loosely through the plates of the series, and means, connected to the ends of the cable and engaging the endmost plates of the series, for holding the plates of the series in contact with each other.

3. A welt holdown comprising a U-shaped series of nested, concavo-convex, cylindrically curved plates, a flexible cable passing loosely through the plates of the series, and springs, connected to the ends of the cable and engaging the endmost plates of the series, for holding the plates of the series in contact with each other.

4. A welt holdown comprising a U-shaped series of nested, concavo-convex, cylindrically curved plates, means for holding said plates in movable contact with each other, and a spring, so tensioned as to tend to straighten the U-shaped series of plates, passing through said plates.

5. A welt holdown comprising a U-shaped, flexible welt pressing member capable of conforming to the forepart of a shoe, movable blocks to which the side portions of said member are attached, and means for continuously exerting upon said blocks a torsional force tending to lift said member and simultaneously tilt said side portions outward.

6. A welt holdown comprising a U-shaped, flexible welt pressing member capable of conforming to the forepart of a shoe, supporting rods extending alongside the side portions of said

member, blocks attached to said side portions and slidably carried on the rods, and combination tension and compression springs connecting the blocks to the respective rods.

7. A welt holddown comprising a U-shaped, flexible welt pressing member capable of conforming to the forepart of a shoe, supporting rods extending alongside the side portions of said member and pivotally mounted for both vertical and horizontal movements, blocks attached to said side portions and slidably carried on the rods, spring means exerting lifting force upon the rods, and spring means exerting upon the rods force tending to move them toward each other.

8. A welt holddown comprising sole gages adapted to engage opposite edges of the forepart of a shoe sole, a U-shaped, flexible welt pressing member disposed above said gages and capable of conforming to the forepart of a shoe, presser plates carried by the sole gages, said plates being movable relatively to said gages and arranged to engage the outer face of the welt pressing member, and spring means for yieldingly pressing each of said plates independently against the outer face of the welt pressing member, to press said member into the welt crease of the shoe.

9. A welt holddown comprising sole gages adapted to engage opposite edges of the forepart of a shoe sole, a U-shaped, flexible welt pressing member disposed above said gages and capable of conforming to the forepart of a shoe, presser

plates carried by the sole gages, said plates being movable relatively to said gages and arranged to engage the outer face of the welt pressing member, spring means for yieldingly pressing each of said plates independently inward against the outer face of the welt pressing member, to press said member into the welt crease of the shoe, and adjustable means for positively limiting outward movement of the plates against the tension of the spring means.

10. In a welt holddown apparatus, a movable welt pressing member, a movable pressure device disposed in co-operative relation to said member and adapted to press said member upon the welt 15 of a shoe, a manually operable cam for moving said pressure device, a lever, and an adjustable pressure transmitter mounted on said lever and engaging the cam and the pressure device, said cam being designed to impart to the transmitter 20 an initial rapid movement of considerable extent followed by a slower movement of less extent with increasing mechanical advantage.
